[57] CLAIM

I claim the ornamental design for a combined resilient safety tile, as shown and described.

DESCRIPTION

FIG. 1—is a prospective view of a combined resilient safety tile broken on one side and the top disclosing indefinite length and width showing my new design;

FIG. 2—is a top view thereof;

FIG. 3—is a side elevational view thereof;

FIG. 4—is a elevational view of the other side;

FIG. 5—is a bottom view;

FIG. 6—is an end elevational view; and,

FIG. 7—is an end elevational view of the opposite end.
